CONSTANT FLOW PUMP

Merton C. Cuthbert, Jacksonville, Fla.

Application July 12, 1941, Serial No. 402,212

1 Claim. (Cl. 103—125)

My invention relates to improvements in non-compressible fluid pumping means, and in particular to constant flow series rotary pumping means, wherein the back flow is substantially reduced and staggered in occurrence, so that the outflow is substantially constant, and the primary object of my invention is to provide a simple and efficient arrangement of this character.

Other important objects and advantages of my invention will be apparent from a reading of the following description taken in connection with the appended drawings, wherein for purposes of illustration I have shown a preferred embodiment of my invention.

In the drawings—

Figure 1 is a side elevational view of the embodiment.

Figure 2 is a top plan view of Figure 1.

Figure 3 is a side elevational view with the side plate removed.

Figure 4 is a perspective view of one of the rotary gates.

Figure 5 is a perspective view of one of the rotary pistons.

Referring in detail to the drawings, the numeral 5 generally designates the pumping elements 6 and 7, respectively, each of which comprises an aligned pair of substantially two-third cylindrical chambers 8 and 9, respectively, at the center of which are respective shafts 10 and 11, which have outside gears 12 and 13 in mesh, the shafts 11 of the two pumping elements being connected together by a sprocket chain 14 trained over sprocket wheels 15 as indicated in Figure 1 of the drawings whereby the two pumping elements are operated together and in phase. A removable side plate 16 held in place by bolts 17 exposes the chambers 8 and 9 as indicated in Figure 3 of the drawings. The two pumping elements are connected by a web or standard 18 which rises from a base 19, and the upper and lower chambers 8 and 9 in each unit are connected in communication by a horizontal passage 20 which has a middle portion 21 which establishes communication between the adjacent sides of the chambers of the two pumping units 6 and 7. The left hand end of the passage 20 is the outflow or discharge of the pumping unit while the right hand end of the passage 20 is the intake.

Keyed on the upper shafts 10 are hourglass gates 22 and 22', while keyed on the lower shafts 11 are the pistons 23 and 23', respectively. The pistons 23 comprise relatively small diameter

5 circular portions 24 which are concentrically mounted on the shafts 11 and from the opposite sides of which radiate diametrically opposed arms 25 and 25', the outer ends of which run close to the peripheral walls of the chambers 9 and extend into the passage 20 as indicated in Figure 3 of the drawings.

The rotary gates 22 and 22' comprise the central parallel sided portion 26 from the opposite ends of which radiate the segmental portions 27, with the peripheral edges of the segmental portions running close to the peripheral wall of the chambers 8, and to the periphery of the circular portions 24 of the pistons 23 and 23'.

10 As indicated in Figure 3 of the drawings the pistons and the rotary gates are arranged on their shafts a quarter revolution apart, so that in the position shown in the left hand unit 6 the maximum size of outflow opening is defined 15 between the piston 24 and the rotary gate 22, so that substantially no restriction is offered to the outflow of the fluid through the passage 20. In similar phase the outflow is similarly 20 unrestricted from the unit 7 into the unit 6.

25 As indicated in Figure 3 of the drawings the pistons and the rotary gates are arranged on their shafts a quarter revolution apart, so that in the position shown in the left hand unit 6 the maximum size of outflow opening is defined 30 between the piston 24 and the rotary gate 22, so that substantially no restriction is offered to the outflow of the fluid through the passage 20. In similar phase the outflow is similarly 35 unrestricted from the unit 7 into the unit 6. It will be observed that in the cases of most 40 rotary pumps there is a great defect in that at some point in the cycle the outflow is greatly restricted with a consequent large loss of energy when the pump is operated at high speed. In the present invention the greatly enlarged size 45 of the outflow opening substantially prevents back flow at this point, so that the fluid under pressure is freely expelled. The efficiency of the pump is further aided by the fact that the pressure on both sides of the recess is at 50 all times equal, with the result that substantially no aid is required to drive the rotors, once the pumping unit has been primed and brought up to operating speed. In the present arrangement as shown in Figure 3 of the drawings, the positions of the rotors, besides being one-quarter of a turn ahead in the case of each pumping element, are arranged in substantially opposite phase and also at a quarter revolution out of phase, so that in the emitting stage the gates and pistons positively prevent back flow from one pumping element to the other.

55 Although I have shown and described herein a preferred embodiment of my invention, it is to be definitely understood that I do not wish to limit the application of the invention thereto except as may be required by the scope of the subjoined claim.

Having described the invention, what is claimed as new is:

A pumping device comprising a housing having a straight flow passage passing therethrough and said housing having a pair of gate chambers therein located to one side of the passage and a pair of piston chambers therein located at the opposite side of the passage, all of said chambers being in communication with the passage with each gate chamber being placed opposite a piston chamber, a rotary gate in each gate chamber of hour-glass form and including

5 a pair of diametrically opposite circumferential segments and deep recesses between the segments flat bottomed and inwardly tapering, a rotary piston in each piston chamber, each piston having 10 a pair of diametrically opposite radial arms for entering the recesses during the revolutions of the parts and means for rotating the gates and pistons in unison and with the sets of gates and pistons being in substantial opposite phases, whereby back flow through the passage is prevented.

MERTON C. CUTHBERT.
